UNITED STATES PATENT OFFICE

EDWARD REUKAUF, JR., OF PHILADELPHIA, PENNSYLVANIA, ASSIGNOR TO CAREY-MCFALL CO., OF PHILADELPHIA, PENNSYLVANIA, A CORPORATION OF PENNSYLVANIA

WINDOW SHADE MECHANISM

Application filed October 31, 1930. Serial No. 492,595.

This invention relates to window shade mechanism, and particularly to the type of mechanism used in automobiles having closed bodies.

5 The object of the present invention is to provide means which will eliminate the noise caused by the roller-retaining pawls striking alternately against the roller spindle and the pawl stops, when the pawls are not in engagement with the retaining shoulders on the curtain spindle.

The above condition arises when the curtain has been raised to its maximum high position, wherein the ends of the draw stick of the curtain are in engagement with the roller-supporting brackets, or when the draw stick is wedged between the rolled curtain and the window frame, or when the guide cords at the sides of the curtain, which pass through guide eyes at the ends of the draw stick, are so taut as to prevent further rotation of the roller, under the influence of the roller spring.

Usually two pawls are provided on a curtain roller and these pawls are loosely pivoted for free movement on the roller, to permit one or the other of the pawls to fall by gravity into contact with a retaining shoulder on the supporting spindle. When the curtain is partly drawn the one retaining pawl is seated in the spindle groove and against the retaining shoulder thereby provided, being held in firm contact with the retaining shoulder under the influence of the roller spring, which at all times is exerting a force on the roller tending to wind the curtain upon the roller, thus when the curtain is partly drawn the one pawl is in firm contact with the shoulder and no rattling of the pawl occurs, the other pawl, however, is free to vibrate and rattle.

When the curtain is fully raised, as above noted, neither of the pawls is in engagement with the retaining shoulder, consequently they are both free to rattle, and this rattling creates an undesirable noise within the vehicle when the vehicle is in motion.

According to the principles of my invention, I provide anti-rattling means between the pawl stops and the pawls, such anti-rattling means comprising, in the present in-

stance, resilient pads, which hold the ineffective pawl or pawls firmly against the outer surface of the spindle, thereby eliminating the movement of the pawls about their pivots, which consequently eliminates the undesirable rattling noise created by such movement.

Referring to the drawings:

Fig. 1 is a front elevational view of the roller and its supporting brackets, showing a portion of the roller and one of the brackets in section;

Fig. 2 is an end view showing the curtain partly drawn;

Fig. 3 is a sectional elevation taken on the line 3—3, Fig. 1, showing the position of the retaining pawls when the curtain is in a partly drawn position, such as illustrated in Fig. 2;

Fig. 4 is an end elevation similar to Fig. 2, but showing the curtain in its maximum raised position;

Fig. 5 is a sectional elevation similar to Fig. 3, showing the pawls in the position assumed when the curtain is fully raised and the draw stick of the curtain is in engagement with the curtain-supporting brackets, as illustrated in Fig. 4;

Fig. 6 is a sectional view taken on the line 6—6, Fig. 3; and

Figs. 7, 8 and 9 illustrate modifications of the invention.

As illustrated in the drawings, the shade mechanism comprises a tubular roller 1 having a closure plate 2 at each of its ends. The closure plates 2 may be secured to the respective ends of the tube 1 in any suitable manner.

The curtain roller 1 is supported by a pair of brackets 3, 3 respectively, which are located at the opposite ends of the roller 1.

Each of the supporting brackets 3 consists of a hollow substantially semi-spherical head 4, which is connected by a relatively narrow neck 5 to a foot plate 6. The foot plate 6 is provided with openings 7, 7 which are adapted to receive screws or similar elements by which the said brackets are secured to the window frame, or to the car body at each side of the window.

Secured to one of the supporting brackets 100

3 is a relatively long spindle 10, which projects through the end closure plate 2 into the tubular curtain roller 1 and is co-axially aligned therewith. Secured to the other of the supporting brackets 3 is a relatively short spindle 11, which, like the spindle 10, is co-axially aligned with the roller 1 and projects into said roller through the closure plate 2. By this means the curtain roller 1 is rotatably mounted on the supporting brackets 3, 3.

In the present instance, the closure plate 2 at one end of the curtain roller 1 is provided with lateral extensions 12, 12, to which one end 13 of a torsion spring 14 is rigidly secured, the opposite end 15 of the said spring being secured to the spindle 10 in any suitable manner.

In the present instance, the diameter of the inner end 15 of the spring 14 is slightly less than the diameter of the adjacent end of the spindle 10, and the said end 15 of the spring 14 is forced on to the said end of the spindle 10 and is consequently rigidly secured thereto.

On the outer side of this particular end plate 2, adjacent the outer end of the spindle 10, is pivotally mounted a pair of retaining pawls 20, 20. The pivots 21, 21 of the pawls 20 are in the form of studs projecting laterally from, and are riveted or otherwise secured to, the said end plate 2.

Each of the pawls 20 is provided with a projection or lip 22. The pawl end 22 of one of the pawls 20 is adapted to project into a retaining notch 23 formed in the cylindrical surface 25 of the spindle 10, while the end 22 of the other of the said pawls rides on the said cylindrical surface of the spindle 10.

Adjacent the outer end of each of the pawls 20 and rigidly secured to, or formed integral with, the end plate 2 of the roller is a pawl stop 26, which limits the movement of the pawl 20 in a direction away from the spindle 10.

The end plate structure 2 on which the pawls 20, 20 are mounted, consists of an inner disc 2^a and outer disc 2^b and an intermediate disc 2^c. The lateral extensions 12, 12 are formed on the intermediate disc 2^c and project through openings formed in the inner disc 2^a. The pawl stops 26 are pressed out of the outer plate 2^b, all as clearly shown in Fig. 6. This end plate structure in the present instance is provided with an annular cap 27 which secures the elements of the end plate structure together and encloses the retaining pawls 20, 20, which are pivotally mounted on the outer side of the structure 2.

The cap ring 27 is spun around the peripheries of the plates 2^a and 2^b of the end plate structure 2, as illustrated at 28, and terminates at one side of the closure structure 2 in an inwardly extending flange 29 which lies against the inner surface of the plate 2^a, and at the opposite side of the closure struc-

ture 2 the ring 27 flares away from the plate 2^b to a plane adjacent the edge of the bracket head 4, to form a casing 30 for enclosing the pawls 20, 20 and the parts co-operating therewith.

While one specific construction for the pawl mounting has been described, obviously the pawls and pawl strips may be mounted on a plate enclosed entirely within the roller and the flanges on the ends of the roller eliminated, without departing from the spirit of the invention.

The curtain roller 1 is adapted to receive the usual form of curtain α , the one end of which is secured to the roller 1 in any desired manner, while the opposite end is provided with a hem α^1 in which is located the draw stick y . This draw stick may extend beyond the side edges of the curtain α , consequently when the curtain is raised to the maximum position illustrated in Fig. 4 the ends of the draw stick will engage the necks 5, 5 of the brackets 3, 3 respectively, the torsion spring 14 tending to rotate the roller 1 and to further wind the curtain α thereon, or the draw stick may have eyes in its opposite ends for the reception of guide cords extending downwardly along the sides of the window to which the curtain is applied, as above noted.

In the position shown in Fig. 5 neither of the retaining pawls 20 are in engagement with the retaining shoulder formed by the wall of the notch 23 which is produced in the supporting spindle 10, consequently the said pawls normally would be free to turn about their pivots 21, which when the vehicle to which the curtain is attached is in motion would permit the said pawls to rattle back and forth and alternately strike the pawl stops 26 and the surface 25 of the spindle 10, there being at all times a slight amount of space provided, between the outer surface 25 of the spindle 10 and the adjacent surface of the pawl stop 26, in excess of the space actually required for the accommodation of the pawl 20 therebetween. This tolerance permits of the motion above noted which under ordinary circumstances results in the above-mentioned rattling and undesirable noise when the vehicle is in motion.

In order to eliminate this undesirable noise, I have placed between the pawl stops 26 and the pawls 20, anti-rattler elements in the form of resilient pads 31, 31, which, when the tip of the projection 22 of the one pawl is riding on the cylindrical surface 25 of the spindle 10, bears against the oppositely disposed edge of the pawl and holds the said tip of the pawl firmly against the said cylindrical surface, and thereby prevents free pivotal movement of the pawl 20 about the pivot 21 thereof. By eliminating this motion the noise resulting therefrom is accordingly eliminated.

In the present instance the pad 31 com-

prises a piece of rubber, or its equivalent, passed through and rigidly held, by its inherent tendency to expand, in an opening 32 formed in the outer plate 2^b of the closure 5 structure 2, intermediate the outer edge of the pawl 20 and the inner surface of the pawl stop 26.

In Fig. 7, I have illustrated a modification 10 of the invention comprising a band of rubber, or equivalently resilient and sound-absorbing material 31^c, which is placed around each of the pawl stops 26. These resilient pads 31^c may be secured to the stops 26 in any suitable manner either by the inherent 15 friction of the material itself, or by a suitable adhesive placed between the stop and the band, or by riveting or by otherwise forming a retaining flange on the outer end of the stop by which the said band would be prevented 20 from moving off the stop to which it is applied.

Obviously in place of the rubber lug 31 or the rubber band 31^c, I may provide a pad 31^b on one side of the stop as clearly shown 25 in Fig. 8, and secure the said pad to the stop in any desired manner. In Fig. 8, the stop 26^b is shown as having a dovetailed slot adapted to receive a correspondingly shaped projection formed on the pad 31^b.

30 In Fig. 9, the pad 31^c is shown as being carried by the pawl 20^c which is provided with a dovetailed slot adapted to receive the tapering sides of the pad 31^c.

When the pawl 20 is in engagement with 35 the retaining shoulder of the spindle the resilient pad 31 is disengaged from the pawl to permit free movement of the pawl into and out of the groove 23, but when the pawl is out of the groove 23 and the tip 22 thereof 0 is resting on the plain surface 25 of the spindle the pad 31 exerts sufficient pressure 5 on the pawl to prevent free movement of the pawl between the spindle 10 and the stop 26. A slight space is provided between the pad 31 and the stop 26 in the preferred form of 5 the invention as shown in Figs. 1 to 6 to provide tolerance for any slight eccentricity of the roller or pawls relative to the axis of the spindle, however, such tolerance may be provided by making the pads, such as shown in the modified form of the invention, Figs. 7, 8 and 9, of a very soft pliable rubber.

From the above description, it will be noted that by providing a resilient element intermediate the outer edge of the pawl and the inner surface of the pawl stop and which tends to maintain the tip of the pawl in firm contact with the plain surface of the spindle, when the pawl is not in engagement with the retaining shoulder of the spindle, I prevent the undesirable noise ordinarily attending the disengaged pawls of the curtains of a moving vehicle.

I claim:

1. In window shade mechanism, compris-

ing a shade roller, a spindle axially aligned with said roller and having a plain surface and a retaining shoulder thereon, a pawl carried by the roller adapted to ride on said surface and to engage said shoulder, the combination therewith of means for maintaining said pawl in contact with said surface when disengaged from said shoulder. 70

2. In window shade mechanism, comprising a shade roller, a spindle axially aligned with said roller and having a groove formed in its surface, a pawl mounted on said roller and adapted for movement toward and away from said spindle, to enter the groove, and to ride on the said surface thereof, the combination therewith of means for maintaining the said pawl in contact with the said surface when disengaged from said groove. 75

3. In window shade mechanism, comprising a shade roller, a spindle axially aligned with said roller and having a groove formed in its surface, a pawl mounted on said roller and adapted for movement toward and away from said spindle, to enter the groove, and to ride on the said surface thereof, the combination therewith of resilient means for maintaining the said pawl in contact with the said surface when disengaged from said groove. 80

4. In window shade mechanism, comprising a shade roller, a spindle axially aligned with said roller and having a groove formed in its surface, a pawl mounted on said roller and adapted for movement toward and away from said spindle, to enter the groove, and ride on the said surface thereof, and a stop 100 to limit the movement of said pawl in a direction away from said spindle, the combination therewith of resilient means for preventing free movement of the pawl between the spindle and the stop when disengaged from 105 said groove.

5. In window shade mechanism, comprising a shade roller, a spindle axially aligned with said roller and having a groove formed in its surface, a pawl mounted on said roller and adapted for movement toward and away from said spindle, to enter the groove and to ride on the said surface, and a stop to limit the movement of said pawl in a direction away from said spindle, the combination therewith of resilient means located between the stop and the pawl for preventing engagement of the pawl with the stop when disengaged from said groove. 110 115

6. In window shade mechanism, comprising a shade roller, a spindle axially aligned with said roller and having a groove formed in its surface, a pawl mounted on said roller and adapted for movement toward and away from said spindle, to enter the groove, and to ride on the said surface, and a stop to limit the movement of said pawl in a direction away from said spindle, the combination therewith of a resilient pad located between the stop and the pawl for preventing direct 120 125 130

engagement between the pawl and the stop when disengaged from said groove.

7. In window shade mechanism, comprising a shade roller, a spindle axially aligned with said roller and having a groove formed in its surface, a pawl mounted on said roller and adapted for movement toward and away from said spindle, to enter the groove and to ride on the said surface, the combination therewith of a resilient projection on the roller adjacent and adapted to engage the outer edge of the pawl to maintain the pawl in firm contact with the said surface of the spindle disengaged from said groove.
8. In window shade mechanism, comprising a shade roller, a spindle axially aligned with said roller and having a groove formed in its surface, a pawl mounted on said roller and adapted for movement toward and away from said spindle, to enter the groove, and to ride on the said surface, and a stop adapted normally to limit the movement of said pawl in a direction away from said spindle, the combination therewith of a lug composed of resilient material and projecting from said roller intermediate said stop and said pawl for maintaining the pawl in firm contact with the said surface of the spindle and to prevent direct engagement of the pawl with the stop, when said pawl is disengaged from said groove.
9. In window shade mechanism, comprising a shade roller, a supporting spindle axially aligned with the roller and provided with a groove in its outer surface, a pawl operatively mounted on the end of the roller in a plane substantially at right angles to the axis of the roller and adapted to ride on the surface of the spindle and to enter the groove therein, and a stop for limiting the outward movement of the pawl relative to the spindle, the combination therewith of a resilient plug mounted in an opening formed in the end of the roller intermediate the outer edge of the pawl and the said stop and extending outwardly from the end of the roller between the said pawl and said stop.
10. In window shade mechanism, comprising a shade roller, a supporting spindle axially aligned with the roller and provided with a groove in its outer surface, a pawl operatively mounted on the end of the roller in a plane substantially at right angles to the axis of the roller and adapted to ride on the surface of the spindle and to enter the groove therein, and a stop for limiting the outward movement of the pawl relative to the spindle, the combination therewith of a resilient plug mounted in an opening formed in the end of the roller intermediate the outer edge of the pawl and the said stop and extending outwardly from the end of the roller between the said pawl and said stop, engaging said pawl when the pawl is disengaged from said groove.

11. In window shade mechanism, comprising a shade roller, a supporting spindle axially aligned with the roller and provided with a groove in its outer surface, a pawl operatively mounted on the end of the roller in a plane substantially at right angles to the axis of the roller and adapted to ride on the surface of the spindle and to enter the groove therein, and a stop for limiting the outward movement of the pawl relative to the spindle, the combination therewith of a resilient plug mounted in an opening formed in the end of the roller intermediate the outer edge of the pawl and the said stop and extending outwardly from the end of the roller between the said pawl and said stop in a position spaced from the stop and engaging said pawl when the pawl is disengaged from said groove.

12. In window shade mechanism, comprising a shade roller, a supporting spindle axially aligned with the roller and provided with a groove in its outer surface, a pawl operatively mounted on the end of the roller in a plane substantially at right angles to the axis of the roller and adapted to ride on the surface of the spindle and to enter the groove therein, and a stop for limiting the outward movement of the pawl relative to the spindle, the combination therewith of a resilient plug mounted in an opening formed in the end of the roller intermediate the outer edge of the pawl and the said stop and extending outwardly from the end of the roller between the said pawl and said stop in a position spaced from the pawl and the stop when the pawl is engaged in said groove and adapted to engage the pawl when said pawl is disengaged from said groove and riding the surface of the spindle.

13. In window shade mechanism, comprising a shade roller, a supporting spindle axially aligned with the roller and provided with a groove in its outer surface, a pawl operatively mounted on the end of the roller in a plane substantially at right angles to the axis of the roller and adapted to ride on the surface of the spindle and to enter the groove therein, and a stop for limiting the outward movement of the pawl relative to the spindle, the combination therewith of a resilient plug mounted in an opening formed in the end of the roller intermediate the outer edge of the pawl and the said stop and extending outwardly from the end of the roller between the said pawl and said stop in a position spaced from the pawl and the stop when the pawl is engaged in said groove and adapted to engage the pawl when said pawl is disengaged from said groove and riding the surface of the spindle and adapted to engage both the pawl and the stop to prevent direct engagement of the pawl with the stop.
